(57) **CLAIM**

We claim the ornamental design for an accessory for a lighting device, as shown and described.

DESCRIPTION

FIG. 1 is a top perspective view of the accessory for a lighting device attached to a light engine.

FIG. 2 is a bottom perspective view of the accessory attached to a light engine.

FIG. 3 is a second bottom perspective view of the accessory.

FIG. 4 is a top view of the accessory.

FIG. 5 is a bottom view of the accessory; and,

FIG. 6 is a right side view of the accessory. The left side view, front view and rear view are mirror images of the right side view.

The broken line illustration of a light engine shown in FIGS. 1 and 2 illustrates environmental structure and forms no part of the claimed design.
